UNITED STATES PATENT OFFICE.

ABEL D. TYLER, JR., OF BROCKTON, MASSACHUSETTS, ASSIGNOR TO THE TYLER MANUFACTURING COMPANY, OF PORTLAND, MAINE.

DOOR-SPRING.

SPECIFICATION forming part of Letters Patent No. 445,101, dated January 20, 1891.

Application filed February 26, 1890. Serial No. 341,898. (No model.)

To all whom it may concern:

Be it known that I, ABEL D. TYLER, Jr., of Brockton, county of Plymouth, State of Massachusetts, have invented an Improvement in 5 Blind Attachments, of which the following description, in connection with the accompanying drawings, is a specification, like letters on the drawings representing like parts.

This invention in window-blinds relates to 10 that class of window-blind which consists of an outer and an inner fold hinged together, the inner fold being hinged to the window-easing.

My invention has for its object to provide 15 a novel connection, as will be described, between the window-frame and the outer fold of the blind, whereby the inner fold of the said blind may always be brought or carried into its true locking position when the blind 20 is opened, the outer fold of the said blind being moved at the same time with the inner fold.

My invention therefore consists in the combination, with a window-frame and a blind 25 hinged thereto, consisting of an outer and an inner fold, of an intermediate connection between the said frame and outer fold of the blind, composed, essentially, of a rod and housing and means to permit of longitudinal movement of the rod, whereby the inner fold of the blind is always brought into its proper place when open, and pivotal connections attaching the rod to the outer fold and housing, substantially as will be described.

30 Other features of my invention will be pointed out in the claims at the end of this specification.

Figure 1 is a front elevation of the outside of a window-frame and a twofold blind attached thereto, to enable my invention to be 35 understood, the said blind being shown closed. Fig. 2 is a top or plan view of the window frame and blind shown in Fig. 1, the said blind being represented by dotted lines in its open 40 position; and Fig. 3, a detail on an enlarged scale to more clearly show the form of connection preferred by me.

The window-frame A, of any usual or well-known construction, having secured to it by 45 hinges A' a twofold blind, consisting of an inner fold a and an outer fold a', secured to-

gether, as by hinges a³, (see Fig. 2,) may be of any usual or well-known construction.

The inner fold a, as herein shown, has secured to it, as by screws a⁴, a slotted, curved, 55 or cam-shaped arm a⁵, which is engaged by the end of a crank or arm a⁶ on a shaft a⁷, extended through the window-frame, as herein shown, from the outer to the inner side thereof, and engaged at its inner end, preferably, by 60 the forked ends of a handle, (not herein shown,) by turning which the arm or crank a⁶ is made to travel in contact with the guide-arm a⁵ and move the inner fold of the blind to open or close the same, according to the 65 direction in which the handle is turned.

In order that the inner fold a of the two-fold blind may be always brought back into its true locking position when the blind is opened, as shown by dotted lines, Fig. 2, I have 70 provided a novel connection between the window-frame A and the outer fold of the blind.

The novel connection referred to, as herein shown, preferably consists of a rod or bar b, having one end secured to the outer fold of 75 the blind, as by an eye or pin b', and its inner end detachably secured, as by a set-screw b², to a crank or arm b³, pivoted on a pin or rod b⁴, secured to or forming part of a reciprocating bar or rod b⁵, located within a housing b⁶, which is secured, as herein shown, by screws b⁷ to the window-frame. The rod b⁵, as shown in Fig. 3, has bearings in annular rings or webs b⁸ b⁹ on the inner side of the housing, and the said rod on opposite sides of 80 the pin b⁴ is encircled by springs c c', having one end bearing against the said pin and their other ends against the rings b⁸ b⁹, the said springs being coiled in opposite directions, so that the slide-bar b⁵ may be centered when 85 the said springs are relieved from tension.

In practice the operator turns the handle connected to the shaft a⁷, so as to move the crank-arm a⁶ in the cam-shaped arm a⁵ to open the inner fold of the blind, and as the 90 said inner fold is opened the outer fold is moved with the inner fold and the said folds brought together, substantially as shown by dotted lines, Fig. 2. In practice it might frequently happen than an obstruction may become lodged between the outer and inner folds of the blind, and if the connection between 100

the outer fold and the casing were rigid and immovable the said obstruction would prevent the inner fold of the blind from being brought back into its true locking position; 5 but by making the connection so as to enable the rod b to have a longitudinal movement, which in the present instance is due to the capability of the rod b^3 to slide in its housing, the inner blind may be brought back into its 10 true locking position, the spring c at such time being compressed.

I have herein shown the blind as operated by mechanism from the inside of the frame; but I do not desire to limit myself in this re- 15 spect, as the said blind may be operated by hand, or other forms of operating mechanism may be used with my improved connection between the frame and the outer fold of the blind.

20 I have herein shown one form of novel connection; but I do not desire to limit myself to the particular form shown. So, also, I have herein shown the housing as secured to the window-frame and the rod as fastened to the 25 outer fold of the blind; but I do not desire to limit myself to the particular construction shown, as the position of parts may be reversed and the housing secured to the outer fold of the blind and the rod to the window-frame; but 30 I prefer the manner of connection shown in the drawings.

It will be understood that the rod b is de- 35 tachably secured to the crank-arm b^3 by a set-screw b^2 , so that a rod of one length may be replaced by a rod of another length if it should be desired to employ the housing with a blind of a different width.

I claim—

1. The combination, with a window-frame 40 and a blind hinged thereto consisting of an outer and an inner fold, of an intermediate connection between the said frame and outer fold of the blind, composed, essentially, of a rod and housing and means to normally center

and also to permit of longitudinal movement 45 of the rod, whereby the inner fold of the blind is always brought into its proper place when open, and pivotal connections attaching the rod to the outer fold and housing, substantially as described. 50

2. The combination, with a window-frame and a blind hinged thereto, and consisting of an outer and an inner fold, of a rod and housing and a spring in said housing encircling 55 said rod to normally center and also permit of longitudinal movement of the rod, said housing and rod being secured to the window-frame and pivotally connected to the outer fold of the blind by an intermediate rod b , substantially as and for the purpose specified. 60

3. The combination, with a window-frame and a blind hinged thereto, consisting of an outer and an inner fold, of a housing, a rod sliding therein, and an intermediate rod de- 65 tachably connected to said housing and pivoted to the housing and blind, respectively, and a spring to permit of longitudinal movement of the sliding rod and also to normally center it, substantially as described.

4. The combination, with a window-frame 70 and blind hinged thereto, consisting of an outer and an inner fold, of a housing rigidly secured to the window-frame, a reciprocating rod b^3 , adapted to slide in said housing, springs inclosing said rod on each side of the 75 crank-arm to normally center it, a crank-arm secured to said rod, and a rod, as b , pivotally secured to the said crank-arm and pivotally connected to the outer fold of the blind, substantially as described. 80

In testimony whereof I have signed my name to this specification in the presence of two subscribing witnesses.

ABEL D. TYLER, JR.
